[57] CLAIM

The ornamental design for a water meter housing, as shown and described.

DESCRIPTION

FIG. 1 is a perspective view of the water meter housing showing our new design;

FIG. 2 is a top plan view thereof;

FIG. 3 is a left side elevational view thereof, the right side being a mirror image thereof;

FIG. 4 is a front elevational view thereof;

FIG. 5 is a rear elevational view thereof;

FIG. 6 is a perspective view thereof when used with another unit assembled thereto;

FIG. 7 is a bottom plan view thereof; and,

FIG. 8 is a perspective view of another embodiment, made of brass, the other views of this embodiment being the same as FIGS. 2-7.

The broken line showing of a coupling unit and register housing are for illustrative purposes only and forms no part of the claimed design.
